LAMINATED SHEET MATERIAL

Chester E. Beecher, Norristown, Pa., assignor to
 The Glassine Paper Company, West Conshohocken, Pa., a corporation of Delaware

Application December 18, 1929

Serial No. 414,864

1 Claim. (Cl. 154—50)

This invention relates to a laminated sheet material and method of making the same and has particular reference to a laminated paper.

In providing containers for such materials as 5 potato chips or the like, which contain a considerable amount of grease, it is customary to use transparent bags through which the contents may be viewed. Heretofore such transparent bags have been generally made of paper having 10 a capacity for resisting grease to a more or less limited degree. However, the paper heretofore used for such purpose is not effectively grease-proof, with the result that it does not prevent the penetration of grease which, on contact with the 15 air, tends to become rancid, to the detriment of the contents. Furthermore, it is customary to print, upon the exterior of such bags, the maker's name and advertising matter, which printing is destroyed or rendered ineffective by the penetrating grease.

It is the object of the present invention to provide a sheet material which will be transparent and at the same time grease and moisture proof to a high degree and which will obviate the objections indicated above in connection with containers for greasy products. It is also an object of the invention to provide an improved method of making such material.

In the accompanying drawing, the figure 30 discloses a diagrammatic cross section of the improved sheet material.

The improved sheet material consists of sheets 2 and 4 which are formed in a known manner by sheeting pure thoroughly hydrated pulp, preferably sulphite pulp of spruce, producing a grease-proof paper, then wetting this sheeted product, and supercalendering by ironing out the wetted sheet by the application of heat and pressure. The material thus produced is grease-proof and 40 also non-absorbent of wax. It is of fine texture and transparent and may be printed upon in the same fashion as ordinary paper. The two sheets 2 and 4 formed in this manner are adhered together by a film of paraffine 6 which, by reason 45 of the fact that the sheets are substantially non-absorbent of either paraffine or other wax, is substantially confined to the inner faces of the sheets. The paraffine is entirely absent from the outer faces of the laminated material.

50 When the two sheets are thus joined by an intermediate film or layer of paraffine, the resultant material is of a high degree of transparency. This transparency is greater than that ordinarily obtained by impregnating ordinary paper with 55 wax.

The resultant material is not only grease, air and moisture proof, but also substantially water-proof. The fact that it is moisture-proof and substantially water-proof is due to the presence of the intermediate film of wax, through which 60 the moisture cannot penetrate even though it may penetrate the outer sheets. On the other hand, the material is grease-proof because the outer sheets are of the grease-proof paper formed in the manner described. These outer 65 sheets also prevent contact between the contents of a bag or package made of the material, so as to avoid imparting the taste of wax thereto as would occur with use of ordinary waxed paper. Inasmuch as the wax does not penetrate the outer 70 layers of the material, the material may be readily formed into bags on the ordinary bag machine, or formed into other desired type of container, and may be readily and permanently 75 printed upon.

The preferred method of forming the material comprises continuously coating the surface of one moving sheet with molten paraffine wax, thereafter applying a second similar sheet to the 80 waxed surface of the first sheet, the composite material being then compressed between rollers with the application of heat so as to firmly adhere the two sheets together with an intermediate very thin film of wax.

While the preferred material is made specifically as described above, it will be understood that material having very similar properties may be made using pulps of other types whereby cheaper grades of the material may be formed. The 85 grease-proof and transparent feature of the paper is secured by thoroughly hydrating pulp, then sheeting and thereafter moistening and ironing out the sheets with the application of 90 heat and pressure. Instead of using paraffine wax to form the intermediate film, it is possible 95 to use other mineral, animal or vegetable waxes which in general are not absorbed by the exterior sheets of this paper.

What I claim and desire to protect by Letters 100 Patent is:

A transparent, grease and moisture proof laminated sheet material consisting of supercalendered sheets of greaseproof paper joined by an intermediate film of wax substantially confined 105 to the inner faces of the sheets.

CHESTER E. BEECHER.
